UNITED STATES PATENT OFFICE.

RALPH H. G. MATHEWS, OF CHICAGO, ILLINOIS.

DESIGN FOR A SPARK-GAP ROTOR.

58,095.

Specification for Design.

Patented June 7, 1921.

Application filed July 14, 1920. Serial No. 396,322. Term of patent 7 years.

To all whom it may concern:

Be it known that I, RALPH H. G. MATHEWS, a citizen of the United States, residing in the city of Chicago, county of Cook, State of Illinois, have invented a new, original, and ornamental Design for Spark-Gap Rotors, of which the following is a specification, reference being had to the accompanying drawing, forming part thereof.

Figure 1 is a front elevational view and Fig. 2 a side elevational view of a spark gap rotor provided with wedge-shaped teeth of my design.

I claim:

The ornamental design for a spark gap rotor, as herein shown.

RALPH H. G. MATHEWS.
